UNITED STATES PATENT OFFICE.

BURTON E. HANEY, OF MEDFORD, OREGON.

LAWN-HOSE HOLDER.

1,223,276.

Specification of Letters Patent. Patented Apr. 17, 1917.

Application filed May 24, 1916. Serial No. 99,584.

To all whom it may concern:

Be it known that I, BURTON E. HANEY, a citizen of the United States, residing at Medford, in the county of Jackson and State of Oregon, have invented a new and useful Lawn-Hose Holder, of which the following is a specification.

The present invention appertains to hose holders, and aims to provide a novel and improved device for holding a lawn or garden hose whereby the water can be directed in the direction desired, the present device being extremely simple and inexpensive in construction, being readily formed from a rod or equivalent stock, and being convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a perspective view of a device as in use.

Fig. 2 is an enlarged sectional detail thereof taken on the line 2—2 of Fig. 1.

Fig. 3 is a side elevation of a modified form.

In carrying out the invention, there is provided a vertical rod 1, which is provided between its ends with a single coil or loop 2 defining the downwardly projecting prong 3 below the loop 2 and adapted to be thrust or forced into the ground for supporting the rod in an upright or inclined position. The loop 2 extends through a complete circle about a substantially horizontal axis with the vertical portions of the rod extending upwardly and downwardly from the ends of said loop. The prong 3 is offset to one side of the body portion of the rod 1, and the loop 2 serves as a stop to limit the movement of the prong 3 into the ground. The loop 2 provides a throat or recess 4 between the upper end of the prong 3 and the lower end of the body portion of the rod 1, which is adapted to snugly receive and hold a hose 5, whereby the nozzle

6 will be held in an inclined position, as clearly illustrated in Fig. 1. The hose will be held tightly by the end portions of the loop 2, the rod being resilient so that the loop can be sprung slightly for receiving the hose in an effective manner.

The upper end of the rod 1 is provided with an angularly extending handle 7 whereby the rod can be conveniently forced into and lifted out of the ground.

The handle 7 is provided with a bent back portion 8, whereby the handle is of loop-shape, and the rod has a portion 9 depending from the portion 8 along the body portion of the rod. The lower end of the portion 9 has a hook 10 for supporting an annular sprinkling head 11 of a hose 12, or the hook 10 may be used to support other sprinkling heads or nozzles.

Fig. 3 illustrates a modification. In this form, the rod 1' has the loop 2' forming the prong 3' and hose holding portion 4', the same as with the first form, and the upper end of the rod 1' has an angularly extending handle 7', but the parts 8, 9 and 10 are eliminated. The modified form is designed especially for holding the hose 5 as illustrated in Fig. 1.

The present device provides a convenient and desirable article of the nature indicated, the prong of the rod being readily forced into the ground, so that the hose can be held in the desired manner. The device can be manufactured cheaply, and fulfills its office in a desirable manner.

Having thus described the invention, what is claimed as new is:

1. A hose holder comprising an upright rod having a single loop between its ends extending through a complete circle about a substantially horizontal axis, said rod having vertical portions projecting upwardly and downwardly from the ends of the loop, the downwardly projecting portion providing a ground entering prong below the loop and offset to one side of the upwardly projecting portion of the rod, the end portions of the loop being adapted to receive and clamp a hose.

2. A hose holder embodying an upright rod having a ground entering prong at its lower end and an angularly extending handle at its upper end, said handle having a bent back portion, said bent back portion having a depending portion extend-

ing along the body portion of the rod, and the depending portion having a hook at its lower end for holding a sprinkling head.

3. A hose holder comprising an upright rod having a loop between its ends providing a ground entering prong therebelow, the rod having an angularly extending handle at its upper end, said handle having a bent back portion, said bent back portion 10 having a depending portion extending

along the body portion of the rod, and the depending portion having a hook at its lower end.

In testimony that I claim the foregoing as my own, I have hereto affixed my signature in the presence of two witnesses.

BURTON E. HANEY.
